UNITED STATES PATENT OFFICE.

LYNN T. LEET, OF MONTREAL, QUEBEC, CANADA, ASSIGNOR, BY MESNE ASSIGNMENTS, TO TULIP CUP CORPORATION, OF NEW YORK, N. Y., A CORPORATION OF DELAWARE.

VENDING MACHINE.

Application filed February 7, 1924. Serial No. 691,120.

The invention relates to a vending machine and particularly to a coin operated device for controlling the delivery of articles one at a time from a suitable magazine or container. The invention is well adapted for controlling the delivery of paper drinking cups one at a time from a nested stack of such cups and it will be particularly described in connection with the dispensing of paper drinking cups, the applicability of the invention, however, not being thus limited.

In accordance with the preferred embodiment of the invention a delivery or dispensing device is provided which is locked against operation until the proper coin is dropped into position, whereupon a detent provided for the operating mechanism may be tripped by the operation of the operating mechanism of the dispenser itself, acting through the coin. Manual pressure on the operating mechanism is transmitted through the coin to the latch tripping mechanism, whereupon the coin drops into the receptacle therefor, and a continuation of the movement serves to dispense the article. By the invention a simple, effective and positive-acting device is provided which will not readily get out of order, which is durable, contains a relatively small number of parts, may be constructed cheaply, and which has various other advantages hereinafter more fully to be described.

An object of the invention is the provision of improved devices of the character referred to above. The invention consists in the novel construction, arrangement and combination of parts hereinafter described, according to the preferred embodiment thereof. Other objects and advantages of the invention will be pointed out more fully in the following specification and the invention will be more particularly pointed out in the appended claims.

In order that a clearer understanding of the invention may be had attention is hereby directed to the accompanying drawings forming part of this application, and illustrating one embodiment of the invention. In the drawings

Fig. 1 represents a side elevation of a cup dispensing machine containing one form of the invention and having certain parts removed;

Fig. 2 is a cross section taken on line 2—2 of Fig. 1;

Fig. 3 is a partial side elevation of a portion of the machine showing the tripping of the detent, and

Fig. 4 is a vertical section taken on line 4—4 of Fig. 2.

Referring to the drawings, the invention is shown as applied to a paper cup dispensing machine of the character described and claimed in application of J. D. Reifsnyder, Serial No. 432,377, cup dispensing machine, filed December 22, 1920. The invention is well adapted for use in connection with a cup dispensing machine of this character but is not limited in its usefulness to such application.

Referring more particularly to the drawings a metal housing 1 is shown having ears 2 for securing it to a wall or other support in vertical position, it being, however, understood that the machine may be adapted to operate in a horizontal position, as well as in a vertical position, in accordance with the invention. A glass tube 3 serves as a container or magazine for nested paper drinking cups, which are to be dispensed one at a time. This container is fitted into a vertical annular flange 4 on the housing 1.

The cup dispensing means comprises, in the embodiment of the device illustrated, two cam like members, 5, 5¹, which are adapted to engage and forcibly separate the cups one by one from the stack in container 3. These cams are arranged to normally support the stack of nested cups which are arranged bottom up in container 3, they also being adapted to forcibly separate the lowermost cup from the stack and eject it while supporting the rest of the stack by engagement with the next adjacent cup.

Cams 5, 5¹, are secured to shafts 6, 6¹, 95 journalled in brackets or webs 7, 8, and 7¹, 8¹, of the housing. Shaft 6 is provided with a pinion 9, and shaft 6¹ with a pinion 9¹.

Cams 5, 5¹, are operated together to eject the lowermost cup of the nested series of cups by a push rod 10 formed as a continuation of a slide bar 11, having toothed projections 12, 13, adapted to mesh with pinions 9, 9¹. A compression spring, 14, is shown as provided between the slide bar 11 and a shoulder, 15, on the housing 1, this spring

being adapted automatically to return the slide bar 11 to its outer position after the pressure is released from the push rod 10, so as to return the gears and cams to their normal positions. The extreme inner movement of the bar is limited by the rear wall 16, and the return movement of the bar is limited by the engagement of the same with the front wall 17 of the housing. The slide 10 bar is guided in its movement by the engagement of its upper surface with the wall 18 and the engagement of its lower surface with the wall 19 of the housing.

The cams 5 are provided with cup engaging surfaces or shoulders 20, 21, the lowermost cup of the nested stack normally resting on the shoulders 20. When the cams are rotated the shoulders 20 will be withdrawn from beneath the cups and the lowermost 20 cup of the stack will be disengaged and ejected by means of the shoulders on the cams indicated at 21. This mechanism need not be described in further detail, inasmuch as the same is fully described in the application 25 of Reifsnyder, referred to.

In accordance with the present invention the slide rod 11 is provided with an abutment or shouldered portion or member 22, which may be secured to, or formed integral 30 with the slide bar. The plate 23 of the housing, on the inner side of which slide rod 11 operates, is provided with a horizontal slot 24 therethrough through which the abutment portion 22 of the slide bar slidably extends.

35 A detent 25 is pivotally mounted adjacent one end, as shown at 26, to the outer face of plate 23. This detent is provided at its opposite end with a nose or offset portion 27, which in the normal position of the parts, 40 as shown in Fig. 1, rests behind abutment 22 to prevent the operative inward movement of push rod 10 to eject the lowermost cup from the nested stack. In the normal position of the parts, as shown in Fig. 1, a 45 slight space may be provided between the rear edge 22¹ of abutment 22 and the shoulder 27 of the detent, so that the push rod may be pushed in the small amount required to bring shoulder 22¹ into engagement with the 50 adjacent face of the lug 27, beyond which position the push rod and slide bar 11 may not be moved. This slight movement of the push bar is insufficient to affect the nested cups in container 3.

55 A plate 28 is provided immediately outside of plate 23, this plate being provided with a vertical coin chute 29 and also having a cut away portion 30 to provide for the movement of the pivoted detent 25 and also 60 of the abutment 22 on the slide bar. A cover plate 31 may be secured immediately outside the plate 28 in which the coin chute is provided.

The slide bar is provided with a laterally 65 extending pin 32 which is in horizontal

alignment with the shoulder portion 22 of the slide bar, at the forward or left hand edge of the coin chute, referring to Fig. 1, this pin constituting a second abutment on the slide bar. The plate 28 may be cut 70 away somewhat, as shown at 33, to make room for the normal position of pin 32 so that the pin will not form an obstruction in the coin chute.

When a suitable coin, for example the cent 75 indicated at 34, is dropped into the coin chute, it will come to rest with one edge thereof resting against the edge 35 of the chute, just below pin 32. On its opposite 80 side the coin will engage against a toe 36 formed on detent 25 and extending downwardly below the pivot 26 thereof. The pin 32 may now be approximately in alignment 85 with the center of the coin, and almost in engagement with the edge of the coin, the lower portion of the toe 36 of the detent being engaged at a point diametrically opposite to pin 32. The coin slot 29 is preferably so curved or shaped as to give the coin a tortuous path, so as to render it difficult to 90 operate the detent by extending a wire or the like through the slot. The edge surface 35 of the slot against which the coin engages may be inclined in the manner indicated.

The coin being thus positioned inward 95 movement of the push rod causes pin 32 to press against one edge of the coin and accordingly causes the opposite edge of the coin to push against the lower portion of toe 36 of the detent so as to swing the detent 100 upwardly into its unlatched position, shown in Fig. 3, the shoulder 27 of the detent preferably rising above shoulder 22¹ on the slide bar before the latter has quite come into engagement therewith. The detent moves 105 upwardly until its upper edge comes into engagement with the upper edge of the cut away portion 30 of plate 28.

The forward edge 37 of toe 36 of the detent will now extend at a substantial inclination to the vertical, as shown in Fig. 3, and will form a fixed guiding surface for the coin, since the upper surface of the detent rests against the upper edge of cut-out portion 30, as stated. Accordingly, as the pressure of push rod 10 continues the pressure of pin 32 against the edge of the coin will result in sliding the coin along the surface 37 of toe 36 and down through the chute, the coin dropping into an appropriate receptacle, (not shown). The movement of the push rod, continued until the slide rod completes its forward movement, results in the operation of cams 5, 5¹, and the ejection 115 of one cup from the machine, after which, pressure on the push rod being released, spring 14 returns the slide bar and coacting parts to their normal positions.

It will be noted that when the slide bar returns to its forward position the forward 120

edge 38 of abutment 22 will engage against the rear surface 39 of toe 36 to positively return detent 25 to its locking position, shown in Fig. 1, with shoulder 27 behind shoulder 22¹ of the slide bar.

It will be noted that with the mechanism described the coin acts positively to transmit pressure from the operating slide bar to the detent so that the inward movement of the slide bar serves positively, through the medium of the coin, to unlatch the detent, the same movement of the slide bar operating the article dispensing or ejecting mechanism. It will also be noted that the detent is positively returned to its latching position on the return movement of the slide bar, neither gravity or direct spring pressure being relied on to return the detent to operative position. Accordingly, the device may be operated in a horizontal position, if desired, instead of in a vertical position. It will also be noted that the pivoted detent is mounted on a fixed part of the apparatus in a position which is well protected by the upper portion of plate 28 from fraudulent manipulation by any one operating through the coin slot. The coin slot and operating parts may, of course, be made accurately to size so that a coin of desired size only will operate the device.

It should be understood that the invention is not limited strictly to the exact details of construction which have been particularly described, but that the same is as broad as is indicated by the accompanying claims.

What I claim is:

1. In a vending machine having a container, the combination of dispensing means providing a downwardly extending coin slot, an operating member extending transversely to said slot, a detent on one side of said slot, adapted to latch said member, said slot having a downwardly and inwardly inclined side portion opposite said detent, said detent and said side portion of said slot serving as supporting stops for a suitable coin inserted in the slot adapted to support in operative position a suitably sized coin, only, and means movable with said member to press the coin against said detent to trip the latter and to unlatch said operating member, on operation of said member, said unlatched member serving to operate the dispensing means of the machine, and the tripping of said detent serving to permit the further dropping of the coin by gravity.

2. In a vending machine, the combination or an operating member, means for latching the same against operation, and means providing a coin-slot so positioned that a coin inserted therein will rest against said latch-

ing means, said operating member being arranged, on operation, to press the coin against said latching means to trip the latter, and also being arranged to positively engage said latching means, on the return movement of said member, to return said latching means to latching position.

3. In a vending machine, the combination of supporting means, an operating member guided for movement thereby, a detent pivoted on said supporting means, and having a lug adapted to latch said member, said supporting means having a downwardly extending coin slot formed thereon, said detent having a laterally-extending toe extending into said slot when said detent is in latching position, and means movable with said member to press a coin in said slot against said toe to unlatch said detent, said toe having a coin-engaging surface adapted cooperatively, with said last named means, to press the coin past the same downwardly and forwardly in said slot after said detent has been unlatched.

4. In a vending machine, the combination of supporting means, an operating member guided for movement thereby, a detent pivoted on said supporting means, and having a lug adapted to latch said member, said supporting means having a coin slot formed thereon, said detent having a laterally-extending toe extending into said slot when said detent is in latching position, and said member having a lateral projection adapted to press a coin against said toe to unlatch said detent when said member is operated and the coin in said slot rests against said toe, and said member having a laterally-extending surface adapted to engage said toe, on the return movement of said member, to positively return said detent to latching position.

5. In a vending machine having a container and means for dispensing articles therefrom one at a time, the combination of a dispensing - means - operating member, adapted, on the inward stroke, to operate the dispensing means of the machine, a spring for returning said member, supporting means, having a coin chute, a detent pivoted to said supporting means with a toe normally extending into said chute and a lug latching said member, a lug on said member adapted to press a coin in said slot against said toe to trip said detent when said member is pushed in, and a lug on said member adapted to engage said toe to return it to latching position when said member again moves out.

In testimony whereof I have signed my name to this specification.

LYNN T. LEET.
